UNITED STATES PATENT OFFICE

JOHN E. MUHLEFELD, OF SCARSDALE, NEW YORK

STEAM BOILER STRUCTURE

Application filed May 11, 1929. Serial No. 362,273.

The particular object of the invention to provide a steam boiler structure of the type which includes a main boiler shell together with upper and lower steam and water drums in communication with the rear end of the shell and in which said drums are integrally connected with each other and with the boiler shell, the wall sections at the point of juncture between the various angularly related parts of the structure being curved on a comparatively large radius whereby the necessity of lapping or welding or riveting or the use of welt strips is avoided. I thus obtain a structure which is not only of the requisite mechanical strength, but which will be comparatively light in weight.

It is a more particular object of the invention to provide a steam boiler structure of the above character in which the upper and lower steam and water drums are connected with the main boiler shell by front, intermediate and rear headers affording communication at such points for the free circulation of the water and steam between the drums and the boiler shell, the spaced walls of each header being integrally joined and connected with the drums and the shell in the manner above stated, and the header walls acting in the nature of diaphragms permitting of expansion and contraction of the walls of said boiler shell and the drums.

With the above and other objects in view, the invention consists in the improved steam boiler structure and in the form, construction and relative arrangement of its several parts as will be hereinafter more fully described, illustrated in the accompanying drawings, and subsequently incorporated in the subjoined claims.

In the drawings, wherein I have illustrated one practical embodiment of the invention and in which similar reference characters designate corresponding parts throughout the several views,—

Figure 1 is a wide elevation of the unitary boiler structure;

Fig. 2 is a rear end elevation thereof;

Fig. 3 is a transverse sectional view taken on the line 3—3 of Fig. 1;

Fig. 4 is a similar sectional view taken on the line 4—4 of Fig. 1;

Fig. 5 is an enlarged longitudinal sectional view through the rear portion of the structure taken substantially on the lines 5—5 of Figs. 2 and 3, and

Fig. 6 is a similar enlarged sectional view through the front portion of the structure taken substantially on the line 6—6 of Fig. 4.

In the accompanying drawings, I have selected for purposes of illustration, a boiler structure designed for use in connection with high powered locomotives, which is generally similar to the fabricated boiler structure shown and described in United States Letters Patent No. 1,611,770. It is to be understood however, as this description proceeds, that the essential features of the present disclosure are likewise applicable to various other types of locomotives, marine or stationary industrial boilers.

In the construction shown in the drawings, the main boiler shell indicated at 5 may be of any predetermined length and diameter. With this shell the upper steam drums 6 and the lower steam and water drums 7 located at opposite sides of the central axial line of the shell are operatively associated. The upper steam drums 6 are of greater length than the lower drums 7 and extend forwardly over the boiler shell 5 as well as rearwardly therefrom.

The forward ends of these upper drums are integrally connected with the wall of the main boiler shell 5 and communicate interiorly with said shell through the medium of a front header indicated at 8. This header is preferably though not necessarily of the general cross sectional form seen in Fig. 4 of the drawings and immediately below the drums 6 the walls of said header merge into the top and side walls of the shell 5.

The forward ends of the lower steam and water drums 7 and also the upper steam drums 6 are likewise integrally connected with the rear end of the boiler shell 5 and in communication with the latter through the medium of an intermediate header 9.

The front wall of this header at its junction with the walls of the drums and the shell 5 is connected therewith by the fillet wall sections of relatively large radius shown at 10, and similar wall sections 11 also connect the rear wall of the header 5 integrally with the upper and lower drums 6 and 7. The forward ends of the upper drums 6 are in like manner integrally joined 10 with the wall of the main boiler shell 5 by the large radius fillet walls 12.

The drums 6 and 7 at their rear ends are connected with each other by the rear header 13, the front wall of which is integrally joined to the drum walls by the large radius fillet connections 14. At the proper location, the spaced walls of this rear header are integrally joined with each other by the continuous transversely curved wall section 15 which bounds the elongated fire opening indicated at 16. At its upper and lower ends the rear wall of the header 13 is provided with spaced manholes indicated at 17 and 18 in communication with the 25 rear ends of the upper and lower drums respectively.

The metal of the header walls surrounding these openings is extended inwardly forming the flanges indicated at 19. It is of course, understood that suitable closure means, constituting no part of my present disclosure is provided for such manholes. Similarly formed manholes indicated at 20 are also provided in the forward ends of the 35 upper and lower drums 6.

The boiler shell 5 at a point spaced forwardly from the front ends of the drums 6 is internally formed with the front end tube and flue sheet 21 which is provided 40 with the openings 22 therethrough to receive the forward ends of the fire tubes and flues, the rear wall of the intermediate header 9 being similarly provided with the openings indicated at 23 to receive the rear ends 45 of said tubes and flues.

Forwardly of the tube and flue sheet 21, the front end portion of the shell 5 constitutes the usual smoke box designated at 24 with the top wall of which the outlet stack 50 25 for the smoke and gases is integrally formed. Between this stack and the flue sheet 21, the top wall of the smoke box is provided with an opening surrounded by a flanged boss indicated at 26 upon which 55 the superheater is mounted and suspended within said smoke box.

Each of the upper steam drums 6 adjacent its forward end is provided with a steam outlet surrounded by the flanged boss 27 60 to which suitable steam dome connections are adapted to be attached. Also the top of the boiler shell 5 in advance of the drum 6 is provided with a steam outlet opening 28 for the safety valve connection.

65 The spaced parallel wall sections of each

of the headers 8, 9 and 13 are rigidly connected in the usual manner by the stay bolts indicated at 29, 30 and 31 respectively.

The space between the lower drums 7 and the upper drums 6 rearwardly of the boiler 70 shall 5 defines the firebox chamber, and the drum walls are provided with the openings indicated at 32 in which the upper and lower ends of vertically extending water tubes (not shown) forming the opposite side 75 walls of the firebox chamber are adapted to be secured in accordance with the usual practice in the art.

From the foregoing description, the several novel features of my new unitary steam boiler structure and the advantages thereof in practical use will be readily understood. The production of this structure in the form of a one piece casting not only greatly expedites the manufacture of such 80 boiler structures in comparison with the time consumed in the production and assemblage of the numerous separate parts of the usual fabricated boiler structure, but also materially reduces production costs by eliminating 85 the use of a large number of machines required in the proper formation of the fabricated parts, and the very material reduction of labor costs incident thereto.

By providing in such a unitary structure, 90 the large radius joint connections between the walls of the vertical headers or water legs and the boiler shell end drums, expansion and contraction in the walls of the latter is permitted without liability of the 95 formation of fractures in said joint connections. Thus the necessity of making frequent repairs which is more or less common in fabricated boiler structures due to opening of the joints and leakage caused by the 100 forces of expansion and contraction will be 105 obviated.

As a result of the progress which has been made in the metallurgical art with reference to the production of castings of steels and other alloy metals, which have the same strength per unit of section as fabricated forged or rolled plates heretofore used in similar structures, it has been made possible 110 to produce such a unitary one piece casting as above described with assurance of the 115 requisite strength and resistance to pressure strains in all parts of the structure.

I have herein shown and described an embodiment of my present improvements as 120 applied to a particular type of steam boiler structure, but in the numerous other boiler types employed for a great variety of different purposes to which the essential features of the present disclosure may be applicable, 125 it is possible that certain variations in the details above referred to may be advantageous or necessary. Accordingly, it is to be understood that in the practical development of the invention, I reserve the priv. 130

ilege of resorting to all such legitimate changes therein as may be fairly embodied within the spirit and scope of the invention as claimed.

5 I claim:

1. A unitary steam boiler structure comprising a boiler shell proper, upper and lower drums extending longitudinally of the boiler shell, and water and steam circulating conduits having their walls integrally formed with the walls of said boiler shell and the drums, and said integral connections consisting of joint forming wall sections curved on a comparatively large radius
10 to permit of relative movement between the walls of the conduits and the walls of said drums and boiler shell.
2. A steam boiler structure comprising a one piece casting of a single metal composition including a boiler shell, longitudinally spaced water legs, and upper and lower drums integrally connected, and the walls of said boiler shell, the water legs and the drums being of substantially uniform thickness whereby the same ratio of contraction and expansion in all parts of said walls is obtained.
20
3. A boiler construction for locomotives, comprising a boiler shell proper, a drum communicating with said shell and extending therefrom, and a header interposed between the boiler shell and drum, and formed integrally with said boiler shell and drum, and said boiler shell and drum being joined
25 to the header by curved wall sections flexibly yielding and of large curvature to permit relative movement between the wall portions of the boiler shell, drum and header during expansion of the same.
30
4. A boiler construction for locomotives, comprising a boiler shell proper, a drum communicating with said shell and extending therefrom, and a header interposed between the boiler shell and drum and formed integrally with said boiler shell and drum, and of large curvature to permit relative movement between the wall portions of the boiler shell, drum and header during expansion of the same, said curved portions and the wall
40 portions of the shell, drum and header there adjacent being of substantially uniform thickness.
45
5. In testimony that I claim the foregoing as my invention, I have signed my name
50 hereto.

JOHN E. MUHLFELD.
